ACOUSTICAL CORRECTION TILE

Gary S. Hurban, Buffalo, N.Y., assignor to National Gypsum Company, Buffalo, N.Y., a corporation of Delaware

Filed June 3, 1965, Ser. No. 85,557

Term of patent 14 years

(Cl. D18—2)

Fig. 1

Fig. 2

Fig. 3

Fig. 4

Fig. 5

FIG. 1 is a front face view of an acoustical correction tile showing my new design;

FIGS. 2 and 3 are front face views of modified forms of acoustical correction tile embodying the new design of my invention;

FIG. 4 is an edge view of the said acoustical correction tile of FIGS. 1 through 3;

FIG. 5 is a sectional view taken along the line 5-5 of FIG. 1.

I claim:

The ornamental design for an acoustical correction tile, as shown and described.
